UNITED STATES PATENT OFFICE.

MILTON J. WILLIAMS, OF CHICAGO, ILLINOIS.

PULVERIZER.

939,771.

Specification of Letters Patent.

Patented Nov. 9, 1909.

Application filed February 16, 1909. Serial No. 478,213.

To all whom it may concern:

Be it known that I, MILTON J. WILLIAMS, a citizen of the United States, residing at Chicago, Illinois, have invented a certain 5 new and useful Improvement in Pulverizers, of which the following is a full, clear, and exact description, such as will enable others skilled in the art to which it appertains to make and use the same, reference being had 10 to the accompanying drawings, forming part of this specification, in which—

Figure 1 is a vertical sectional view through a pulverizer constructed according to my improvement. Fig. 2 is a horizontal, 15 fragmentary sectional view through the same.

This invention relates to a new and useful improvement in pulverizers of that type commercially known as the "Williams mills", characterized by the pivoted revolving hammers which act upon the material as it enters the machine at the hopper, or breaker plate, as it is sometimes called, the material being further disintegrated or 20 crushed by the hammers acting thereon as the material is carried over the cage or grinding surface. The crushed material falls through the openings in the cage or grinding surface into a suitable receptacle 25 located beneath the machine. The hammers or beaters which revolve about the shaft, while made of a material whose resistance to wear is its essential quality, will, in time, wear away at their striking ends, and the 30 farther these grinding ends are removed from the breaker plate and grinding surface, the less becomes the capacity of the machine.

It is the purpose of my present invention to provide means whereby these revolving 35 hammers or beaters may be adjusted outwardly to take up this wear (or inwardly, if occasion requires, as when a new cage is introduced to replace a worn one), said means being operable preferably from the 40 inside of the casing by relative rotary movement between two parts and effecting the simultaneous and uniform adjustment of all 45 of the hammers or beaters.

In the drawings, 1 indicates the casing, 2 50 the breaker plate, 3 the grinding surface or cage, and 4 the cover of the machine, which may or may not be hung, as desired.

5 is a shaft mounted in bearings in the side frames of the machine, one end of said 55 shaft carrying a pulley and the other end a balance wheel, neither of these being shown.

6 are disks fixed to shaft 5, said disks being provided with suitable openings in which are mounted through-bolts 7. On these through-bolts are mounted levers 8 whose inner ends are preferably hooked and in whose outer ends are supported hammers or beaters 9. Disks 6 are slotted, as at 10, for the passage of adjusting rods 11 mounted in heads or disks 12 loosely arranged on shaft 65 5. The movable disks 12 are locked in their rotary adjusted positions by means of bolts 13 passing through suitable openings 14 therein and into the holes of disks 6. There may be as many of these openings and bolts 70 as desired for effecting the various adjustments.

In operation, when the hammers 9 are new, levers 8 rest with their hooked points upon the rods 11. When the ends of the 75 hammers become worn, the bolts 13 are withdrawn and the movable disks 12 circumferentially adjusted so as to locate bars 11 in such positions that the inner ends of the levers 8 may move inwardly, and the hammers 9 outwardly to take up the wear of the latter. These adjustments are made from time to time, after each adjustment the bolts 13 being inserted and screwed home so as 80 to fix the relation of the movable disks 12 85 with respect to the fixed disks 6.

In order to prevent the hammers 9 and the levers 8 from falling so as to dull the edge of the striking points of the hammers, should sharp hammers be employed, I provide bolts 90 15, shown in Fig. 1.

By referring to Fig. 2 it will be seen that there is a common bolt 7 from which all of the levers are mounted and also a common pivot bolt for all of the hammers 9.

I am aware that minor changes in the construction, arrangement and combination of the several parts of my device can be made and substituted for those herein shown and described without in the least departing 100 from the nature and principle of my invention.

In using the expression "disks" in the foregoing specification and in the following claims, I wish to be understood as not confining myself to circular disks, as the parts which perform the functions of the supporting disks described and claimed could be in the shape of spider-arms, or other forms, metal being cut away at various places, 105 where it was not needed, to lighten the machine.

Having thus described my invention, what I claim is:

1. In a pulverizer, the combination with a casing, of a shaft, a frame fixed thereon within the casing, a series of sets of hammer supports pivotally arranged in the frame, revolving hammers pivotally carried by the hammer supports and an adjustable means arranged for rotation on the shaft and engaging the inner ends of all of the hammer supports.
2. In a pulverizer, the combination with a casing, a shaft, disks fixed to said shaft, levers pivotally supported between said disks, revolving hammers pivotally carried by the outer ends of said levers and rotatable means coöperating with the inner ends of said levers for adjusting the hammers inwardly and outwardly.
3. In a pulverizer, the combination with a casing, a shaft mounted in the casing, disks fixed to said shaft, levers pivotally mounted upon said disks, revolving hammers carried by said levers, disks rotatably mounted on said shaft, means for locking the last mentioned disks in their rotatably adjusted positions, and means carried by said rotary disks and coöperating with said levers for adjusting said hammers, to move the hammers outwardly to take up the wear.
4. In a pulverizer, a casing, a shaft journaled for rotation therein, disks fixed on said shaft, in which disks are formed a series of concentric slots, rods passing through corresponding slots, a series of sets of levers pivotally held between the disks, the inner ends of which levers bear upon the rods, revolving hammers pivotally carried by the outer ends of said levers, and rod-adjusting means located on the shaft adjacent to the disks and engaging the ends of all of the rods.
5. In a pulverizer, a casing, a shaft journaled for rotation therein, disks fixed on said shaft, in which disks are formed a series of concentric slots, rods passing through corresponding slots, a series of sets of levers pivotally held between the disks, the inner ends of which levers bear upon the rods, revolving hammers pivotally carried by the outer ends of said levers, rod-adjusting means located on the shaft adjacent to the disks and engaging the ends of all the rods, and means whereby the rod-adjusting means is locked to the disks after adjustment.

In testimony whereof I hereunto affix my signature in the presence of two witnesses, this 8th day of February, 1909.

MILTON J. WILLIAMS.
